YARN SPOOL

Edgar F. Hathaway, Wellesley, and Walter Bixby,
Boston, Mass.

Application May 14, 1931. Serial No. 537,304

3 Claims. (Cl. 139—10)

This invention relates to yarn spool construction, and is particularly intended to provide a simple, economical and reliable means of rotatably supporting the yarn spool, especially a sectional yarn spool, in suitable bearings and is especially applicable to service where it is desired that the sections of the spool, which rotate in unison, have the end heads of the section separated from each other by only a small intervening space sufficient to receive a narrow intermediate bearing bracket or stand as in the case of an Axminster tube frame spool.

To this end the invention embraces a sectional spool, whose sections are placed in coaxial alignment end to end for rotatable support in suitable end brackets and intermediate brackets, a supporting gudgeon being employed to have proper bearing support in the intermediate bracket while rotatively interlocking the adjacent ends of the spool sections together to cause them to rotate in unison as the yarn tufts or ends are unwound from the spool sections for delivery to the loom. This and other features of the invention will be fully described in the following specification and will be defined in the claims hereto annexed.

In the accompanying drawings is illustrated two of the forms under which the principles of this invention may be embodied, in which

Fig. 1 is a front elevation, partly in section, of a tube frame of well known type in which is mounted a sectional spool embodying the principles of this invention.

Fig. 2 is a detail view showing principally in central section one end head of one of the spool sections.

Fig. 3 is an end elevation of the head shown in Fig. 2.

Fig. 4 is a central vertical section of the complementary end head of the next adjacent spool.

Fig. 5 is an end elevation of the spool head shown in Fig. 4.

Fig. 6 is a detail view showing one of the end journals and its ejecting spring separated therefrom.

Fig. 7 is a detail view, principally in central section, showing the construction of the intermediate bearing.

Fig. 8 is a side elevation of the bearing bracket shown in Fig. 7.

Fig. 9 is a front elevation of a modified form of tube frame spool, parts of the spool being shown in vertical central section.

Fig. 10 is a detail view of the modification, showing one end of one of the spool sections, chiefly in central vertical section.

Fig. 11 is a side elevation of the head shown in Fig. 10.

Fig. 12 is a detail view of one of the interlocking sectional gudgeons on a vertical central section thereof shown in Fig. 10.

To illustrate the construction and mode of use of this invention according to its practice in the form shown in Fig. 1, there is illustrated a substantially complete tube frame of well known construction comprising a longitudinal carrier bar 1, to opposite ends of which are secured well known types of chain-engaging suspension brackets 2 each provided with an upstanding bearing extension or ear 4 provided with a bearing opening for the reception and support of the end supporting journal of the adjacent spool section. On the front face of the carrier bar 1 is secured a row of side by side parallel tuft-receiving and guiding tubes 3.

The spool section comprises a tubular barrel 5 to which is secured the end head 6 in any suitable manner, as by means of an annular connecting flange at 6^b. The end head usually has an annular flange 6^a at its periphery. Inside the end head is secured in any suitable manner a reenforcing disc 8, whose middle or central portion is struck outwardly to form a bearing hub 8^a in which is inserted and secured a bearing bushing 9 for the support of the outer end of the bearing pintle or journal 12. Before the reenforcing plate 8 is secured in place, a smaller disc 10 is forced into the interior of the flanged portion 6^b of the head 6 and is firmly secured there by soldering or welding operations. A helical or spiral compression spring 13 is inserted between the disc 10 and the shoulder member of the pintle 12 to normally thrust the pintle outward into its supporting bearing, while allowing it to be pushed inward for removal from the bearing when it is desired to remove the spool from its support.

A similar end head 7 is secured by a flanged connection 7^b with the opposite end of the spool barrel 5. On the outer face of this end head 7 is secured a reenforcing disc or plate 17, which extends straight across the open end of the spool and is provided with a central perforation adapted to receive a reduced shank portion 20^a of a bearing gudgeon 20 for revolubly supporting the adjacent ends of both spool sections and rotatably coupling them together. The projecting end of this bearing gudgeon, forming a support for both adjacent spool ends, is in the form of a narrow cylindrical bearing member 20^b and a polygonal head, whose corners

are in registry with the cylindrical bearing member 20b. For convenience in manufacture, the cylindrical bearing portion of this gudgeon may be in the form of a washer or ring slipped over the reduced shank member 20a.

5 The adjacent spool section head 7 is provided with a reenforcing disc 17a, whose central area is punched out or perforated to form a polygonal hole into which the polygonal extension of the bearing gudgeon 20 projects. This construction permits the use of a very narrow intermediate bearing for supporting the adjacent ends of two spool sections, since the gudgeon projects from one section a substantial distance through the end plate into the adjacent section, and there 10 is no danger of displacement of such a gudgeon from a narrow bearing in contradistinction to the construction heretofore commonly used, in which each of the adjacent spool sections are provided with short independent gudgeons whose 15 end faces abut against each other, which requires a supporting bearing of considerable width. Consequently, in this case the intermediate bearing bracket may be made of sheet metal plates 20 secured together face to face and having right angle feet 22a for attaching them to the top 25 face of the carrier bar. At a point in line with the central axis of the spool sections, this intermediate bracket is perforated to receive a narrow bearing bushing 23, whose opposite 30 peripheral edges are upset, or headed down, after the fashion of a rivet to secure the two upright plates together and afford a suitable bearing for the cylindrical member 20b of the gudgeon. It will therefore be seen that the gudgeon forms 35 a common support for revolvably supporting both spool sections and at the same time, through its being fastened to one spool section and having interlocking engagement with the other spool section, equal rotation of the two spool sections 40 in unison is secured.

The advantage of this narrow bearing construction is that the spool heads can be brought very close together and, consequently, there is 45 very little deflection of the yarn tuft elements that are wound close against the spool head and that have to pass through the two tuft tubes 3 on either side of the medial plane of the bearing bracket between the spool sections. As 50 shown in the drawings, this deflection is so slight as to prevent injurious rubbing of the spool head against the yarn elements passing into these two middle tubes and, furthermore prevents chaffing of these yarn elements against the thin 55 end edges of the said tuft tubes, which is a decided advantage in the operation of a tube frame.

As shown in Fig. 9 this gudgeon, having attachment to one of the spool section ends and projecting through the bearing into the other spool section, may be made in sections or halves. In this case the supporting and interlocking gudgeon is formed in two sections, each being substantially 60 semi-circular in contour and each being secured to one spool section to project through the bearing into the interior of the adjacent spool section. A simple and economical form of this sectional gudgeon construction, shown in Figs. 9 to 65 12 inclusive, comprises a sheet metal member 25 pressed into a semi-cylindrical shape with an outwardly projecting attaching flange 25a and a transverse end member 25b. In each case the sectional gudgeon member is inserted through an aperture in its supporting spool head member 18 with its semi-cylindrical surface fitted snugly into 75 the corresponding portion of the aperture, so that

its attaching flange 25a overlaps the inside edge of the aperture in the disc 18. The members are so proportioned in relation to the whole circular aperture that the plane of the inner edge of the gudgeon member coincides not only with the diametrical chord of the aperture in which it is inserted, but also with the diametrical plane of the spool. The companion section of the gudgeon is secured in similar fashion to the adjacent end of the next spool section and projects through the bearing bracket into the interior of the spool section to which the other member is fastened.

80 In this case both plates 18 are provided with circular gudgeon-receiving apertures, one-half of each of which is occupied by an attached gudgeon section adapted to project through the opposed half of the aperture in the adjacent section. The two flat or chord faces, or edges, of these gudgeon sections form an interlocking engagement with each other that necessitates the rotation of both 85 spool sections in unison. One advantage of this sectional construction of the gudgeon, whether made of sheet metal or otherwise, is that both spool sections are of identical construction, thus readily permitting substitution or reversal. This 90 95 construction equally with the form shown in Fig. 1 serves to provide a common support for revolvably carrying two end spools and permits the use of a very narrow intermediate bracket without danger of the gudgeon accidentally falling out of 100 its bearing with slight longitudinal play, which is usually permitted these spools.

A somewhat different form of intermediate bracket is shown in this case, although any suitable form of intermediate bracket may be used. 105 The form shown comprises two side by side sheet metal plates or strips 26 mounted on a common pivot member 27 supported in bearing ears 28 attached to the carrier bar and having their central areas perforated to form cylindrical openings, the 110 edges of which, as shown at 26a, are turned slightly outward to slightly increase the width of the bearing portion which receives the sectional gudgeon and forms a support therefor.

115 What we claim is:

1. A yarn spool embracing in its construction, two coaxially aligned spool sections, an interposed bearing bracket provided with a bearing opening concentric with the axis of revolution of said spool sections, and a two-part bearing gudgeon each 120 part projected from the end of one spool section into the interior of the other spool section through said bearing aperture in mutually lengthwise overlapping relation, the two members of the 125 gudgeon forming a cylindrical bearing support 130 fitting into said bearing opening and revolvably supporting both spool sections.

2. A yarn spool embracing in its construction, two separate spool sections arranged in coaxial 135 alignment with each other associated with an interposed bearing bracket provided with a circular bearing opening, a two-part supporting gudgeon rotatably mounted in said bearing opening and divided from each other on a diametrical plane 140 coinciding with a diametrical plane of said spool sections, each gudgeon member being secured to the end of one spool in position to occupy one-half 145 of said bearing opening and extending into the interior of the adjacent end of the other spool whereby they form a rotatable support for the adjacent ends of both spool sections and by their mutual engagement with each other on a diametrical plane cause both sections to rotate in unison 150 when either is rotated.

3. A gudgeon construction for coupling together coaxially disposed sections of a revoluble spool embracing, two semi-cylindrical members, each provided at one end with a peripherally projecting attaching flange secured to the edge of a circular containing opening so as to lie on one side of the diametrical plane of said opening and projecting into the corresponding portion of an opening in the other spool whereby the gudgeons, when assembled in overlapped relation, form a rotative coupling for supporting adjacent spool sections in rotatively coupled relation.
